T. MANEY

CLAW BAR

Filed June 10, 1927

UNITED STATES PATENT OFFICE.

THOMAS MANEY, OF LOUISVILLE, KENTUCKY.

CLAW BAR.

Application filed June 10, 1927. Serial No. 197,884.

My invention relates to an improvement in claw bars.

The object is to provide a bar particularly adapted for loosening and pulling railway spikes.

In the accompanying drawings:—

Fig. 1 is a fragmentary plan view; and

Fig. 2 is a fragmentary side view showing a rail and tie-plate in section.

10 The numeral 1 represents an extended tip, of which there are two, and 2 is the fulcrum point. In the recess 3, at the center, a claw 4 is formed for straddling the spike and entering between the head of the spike and the tie-plate 5. The numeral 6 indicates the base of the rail, and 7 is the spike to be drawn.

The numeral 8 represents the arm or handle of the claw bar.

20 Under many conditions, a spike may be easily pulled by simply sliding the claw 4 into the space between the head of the spike and the tie-plate, as illustrated in the drawings, whereupon the bar is pulled in a direction away from the rail, rocking on the fulcrum point 2, until the spike is started and pulled out. But spikes are often over-driven and the back of the head becomes so much depressed that it is difficult to in-

30 sert the pulling edges of the claw under the spike head. But if, with the extended tips 1, the handle of the bar is pushed forward, toward the rail, the initial pull is about the higher fulcrum point *a*, at the very end of the tip, with a shoulder lever arm from *a* to *b*, the effect being more power, a better direction of pull and a better hold upon the spike head.

The act of drawing a spike would be about 40 as follows:—

First, thrust the claw as far as possible under the head; throw the top of the bar

forward toward the rail with the tip of the claw as a fulcrum; then, with the slack obtained by the lift the claw has given the 45 spike, insert the claw fully under the head of the spike, and by drawing with a backward or outward pull of the bar handle, the spike is easily removed.

In this way, a simple and powerful device 50 is provided for pulling the most obstinately secured spikes.

By this construction the fulcrum point is shifted to a position in front of the spike instead of behind, as heretofore. In that 55 way, the fulcrum point is higher than the point beneath the head of the spike, from which the spike is pulled and, when in use, the short lever arm from *a* to *b* does not lengthen, consequently retaining its initial 60 power.

The offset of the claw 4 at 3 is necessary in order to give this full effect and at the same time permits the insertion of the pulling flanges at the lowest point. 65

To summarize, in case of an obstinate, over-driven spike, the points 1 are used merely to start the spike, thereby giving clearance for the claws, the final pull being made from the stirrup fulcrum 9 at the 70 rear.

I claim:

1. A claw bar having a claw carried thereby, and provided with offset claw points.

2. A claw bar having a claw carried thereby, and provided with offset claw points on one side of the claw providing an additional fulcrum for the claw bar. 75

3. A claw bar having a claw formed on an end thereof, and provided with extended 80 tips, offset to one side of the claw and forming an additional fulcrum for the claw bar.

In testimony whereof I affix my signature.
THOMAS MANEY.
